SLIP

David I. Klein, New York, N. Y.

Application May 3, 1946, Serial No. 666,996

1 Claim. (Cl. 2-73)

1

This invention relates to ladies' garments, and has for its principal object the provision of a novel slip formed from bias and straight panels and having an increased measure of comfort for the wearer and also improved fitting qualities, particularly throughout the waist-encircling sections. The garment of the present invention has superior fitting qualities in all sizes, although it has been particularly designed for bringing out the best features of smaller figures which frequently have relatively wide shoulders compared with the waist and torso.

Thus, another object of the invention is to provide a garment which easily passes over the head of the wearer, and which, when in place on the body, drapes the figure in a flattering manner and is principally characterized by the absence of excess material or bulging.

A further object of the invention is to provide a garment which is simple to construct, all of the seams being straight or substantially straight. The garment consists essentially of front and rear panels which extend from top to bottom, two side skirt panels, and two side waist panels. The side skirt panels are so disposed as to have their grain line substantially on the straight of the material, thus to give the garment non-stretching characteristics where resilience is not needed. The remaining panels are on the bias, the bias portions cooperating with the straight panels to enable the garment to conform to the body at all times.

In the drawings:

Fig. 1 is a partial front and side elevation of a garment embodying the present invention in position upon the wearer.

Fig. 2 is a similar view showing a partial rear and side elevation.

Fig. 3 is a front elevation of the garment when laid flat.

Fig. 4 is a similar view of the rear of the garment.

Fig. 5 is a pattern showing the several blanks employed in constructing the garment of the present invention.

Referring now to Fig. 5, which shows the pattern of the garment, there is a blank 10 forming a front panel, a blank 11 forming a rear panel, two blanks 12 of similar shape forming side skirt panels, and two blanks 13 forming side waist panels.

Front panel 10 is formed with a slightly-curved, lower edge 14, and inwardly-inclined, vertical edges 15. At or about point 16, which coincides with the waist line of the garment, edges 15 become concavely-curved, as shown at 17, and ter-

minate at points 18. From the upper edge of the garment there are two diagonally-inclined edges 19 which meet at point 20, which coincide with the front median line of the garment. These 5 two latter edges form a substantially V shaped neckline for the garment, although the contour of the neckline may be appropriately modified. Blank 10 is desirably formed generally on a bias relative to the grain line of the material to provide a bias front panel which aids in giving the 10 garment an approved measure of circumferential elasticity.

Rear panel 11 is generally of the same shape as panel 10, although it is somewhat shorter. 15 Thus, it includes a lower edge 24, substantially-straight side edges 25 terminating at their upper ends in concavely-curved sections 26, and an upper edge which may be V-shaped and defined by edge sections 27-27. The V-shaped upper edge 20 is preferred for garments of smaller sizes, although a substantially-straight edge is usually preferred for larger sizes. This rear panel is likewise preferably formed on the bias of the material relative to the vertical median line of the 25 slip.

Side skirt panel 12, of which two are employed, is generally on the straight of the material and is provided with a curved lower edge 30, substantially-straight, inwardly-inclined, vertical 30 edges 29 and 31, and an upper, concavely-curved edge 32. Side waist panel 13, of which two are employed, is provided with a lower, concavely-curved edge 33, an upwardly and outwardly-inclined, substantially-straight edge 34, a down- 35 wardly and inwardly-inclined, upper edge section 35, an upwardly and outwardly-inclined, substantially-straight edge section 36, and a convexly-curved edge 37. These blanks are desirably formed on the bias of the material.

40 The combined length of edge 31 of blank 12 and of edge 37 of blank 13 is substantially the same as the full length of edge sections 15 and 17 of blank 10. Likewise, edge 32 of blank 12 and edge 33 of blank 13 are of substantially the 45 same length. In constructing the garment, these latter edges may first be joined together to form a stitch line 39 which coincides generally with the waist line of the garment. This forms the side waist and skirt panel for the garment, and a 50 similar panel is employed on the other side of the garment. Next, edge sections 31-37 of the side panel are joined to edge sections 15 and 17 of blank 10, forming stitch line 40 on each side of the garment. Edge sections 29-34 of the side 55 panel have a combined length equal substantially

to the length of edge sections 25 and 26 of blank 11. Edge sections 29 and 34 are then joined to edge sections 25 and 26 to form a stitch line 42 on each side of the garment.

The garment is then complete, except for the attachment of shoulder strap elements 44 on each side of the garment. If desired, the upper edge of the waist portion may be finished with lace, as shown at 45.

It will be seen from the foregoing that the contour and grain line of each of the blanks forming the garment have been chosen to provide a well-fitting, unitary body garment having the characteristics earlier pointed out. Horizontal stitch lines 39, at the waist line, each extend substantially one-quarter the distance around the garment on opposed sides thereof. In forming this stitch line on each of the side panels, it is of considerable advantage to form the meeting edges with concave curves in order to give the improved fitting qualities of the present garment. Thus, although the garment has a well-defined waist line, the remaining portion of the waist line, having no horizontal stitch line, permits the garment to accommodate itself to the body of the wearer 25 regardless of the position of such wearer.

While one form or embodiment of the invention has been shown and described herein for illustrative purposes, and the construction and arrangement incidental to a specific application thereof have been disclosed and discussed in detail, it is to be understood that the invention is limited neither to the mere details or relative arrangement of parts, nor to its specific embodiment shown herein; but that extensive deviations from the illustrated form or embodiment of the invention may be made without departing from the principles thereof.

What I claim is:

A ladies' garment formed from a plurality of 40

blanks of material including generally similarly-shaped blanks forming front and rear panels and extending from the upper to the lower edge of the garment, each of such blanks having a curved lower edge, inwardly-inclined vertical edges which terminate in outwardly-curved edge sections, and substantially V shaped upper edges forming the front and rear upper edges, respectively, of the garment, and side panels, each formed from a skirt blank having a curved lower edge, inwardly-inclined vertical edges, and a concavely-curved upper edge, and a waist blank having a concavely-curved lower edge which is joined to the upper edge of the skirt blank to form a waist-line seam, the waist blank further having a convexly-curved edge adjacent the front panel, the grain line of the material in the skirt blanks lying generally on the straight relative to a vertical median line of the garment, and the grain line of the material in the remaining blanks lying on a bias relative thereto, the opposed edges of the side panels being joined to the adjacent edges of the front and rear panels.

DAVID I. KLEIN.
